DISPLAY RACK

Robert L. Sinclair, Dedham, Mass., assignor to The Gillette Company, Boston, Mass., a corporation of Delaware

Application December 24, 1953, Serial No. 400,288

2 Claims. (Cl. 248—198)

This invention comprises a new and improved display rack for exhibiting in show-windows and on show-cases small articles such as safety razor cases, blade packages and the like. It is of the general type constructed and arranged to be supplied in flat knocked-down condition and then by simple manipulation organized to stand securely with an extended base upon a flat surface with a three dimensional appearance, or to serve equally well in suspended condition.

An object of the invention is to provide at moderate cost a display rack having the characteristics above enumerated. Going more into detail, the display rack of this invention comprises an upright easel panel having a section hinged to its front face and a supporting panel hinged to its rear face, together with a connecting element arranged to cause simultaneous movement of the hinged section and panel from flat collapsed condition on opposite sides of the easel panel to a position in which the front section extends forwardly and the supporting panel extends at right angles to the rear face of the easel panel. The mechanism for effecting these movements in diverse planes constitutes an important feature of the invention. The desired results may be effected simply and reliably by arranging the hinged section to swing about a horizontal axis while the supporting panel is hinged to swing about a vertical axis, and by connecting one edge of these members by a band and slit, the slit being formed in the easel panel and the band passing from one edge of the hinged section to the lower portion of the supporting panel. When the hinged section is swung forwardly from its collapsed position, the supporting panel is forced to assume a position at right angles to the rear of the easel panel, and thus engages its rear face along an edge substantially aligned with the slit. When the hinged section is swung back into its collapsed position, the supporting panel is simultaneously turned and twisted out of its supporting position until it arrives at a flat collapsed position upon the rear face of the easel panel.

These and other features and advantages of the invention will be best understood and appreciated from the following description of a preferred embodiment thereof selected for purposes of illustration and shown in the accompanying drawings in which:

Figs. 1 and 2 are plan views of the display rack shown in collapsed position as seen respectively from the front and back.

Figs. 3 and 4 are respectively views in plan and side elevation of the rack in erected condition.

Fig. 5 is a view of the rack in side elevation in partially collapsed position, and

Fig. 6 is a similar view showing the rack in fully collapsed position.

As herein shown the main body of the rack comprises an upright easel section 10 approximately rectangular in shape, although it may be made to conform in contour with any desired ornamentation. Upon the easel panel

2

are depicted two vertical rows of rectangular display areas 11 in each of which is provided a cut-out tongue 12 upon which may be suspended the articles to be displayed. A quadrant-shaped cut-out 13 is provided in the lower edge of the easel panel and into this leads a vertical slit 14. A stop ear 15 projects into the cut-out quadrant from the inner straight edge thereof.

A rectangular tongue or flap 16 is cut in the easel panel midway between the slit 14 and the right-hand edge of the panel as seen in Fig. 1 being shaped to swing outwardly at its lower edge. To this flap is stapled a sectional panel 17 rectangular in contour and having depicted thereon a display area 11' similar to one of the areas 11 of the easel panel. The sectional panel is also provided with a cut-out tongue 19, as are the display areas of the panel itself. The inner edge of the sectional panel 17 is connected by an integral flexible band 18 with the side edge of a supporting panel 20 near its bottom, the band 18 extending through the slit 14 above the ear 15. The supporting panel 20 is substantially triangular in shape having a straight lower edge 21 and a straight upright edge 22 which in the erected position of the display rack as shown in Figs. 3 and 4 engages the rear face of the easel panel along an edge aligned with the split 14 and stands at right angles to the easel panel. The lower edge 21 of the supporting panel terminates in a notch providing an edge which contacts with the stop ear 15 in the erected position of the rack. In this position the sectional panel 17 is shown in Fig. 4 as extending outwardly and downwardly from the easel panel 10. It will be apparent from an inspection of Figs. 3 and 4 that the supporting panel 20 is held firmly in its right-angled supporting position. It is moved into and locks itself in this position when the section 17 is swung forwardly as shown in Figs. 3 and 4. When the section 17 is pressed rearwardly, it causes the supporting panel 20 simultaneously to fold about the slit 14 and to twist toward the left as seen in Fig. 2 until it lies collapsed in flat position upon the back of the easel panel 10. At the same time, the section 17 arrives in its fully collapsed position as shown in Fig. 6. This is caused partly by the drawing of the lower inclined edge of the band 18 inwardly over the edge of the vertical slit 14, while the twisting movement of the supporting panel is facilitated by the rounded shape of its upper end.

All parts of the display rack may be made of stiff resilient cardboard or the like and may be dyed and provided with the necessary tongues and slits at a single operation. The ensuing assembling operation consists merely of interlocking the easel panel between the hinged section 17 and the supporting panel 20 positioned as shown in Fig. 2 and inserting a pair of spaced staples through the flap 16 in the upper edge of the section 17.

In swinging the section 17 rearwardly the tip of the supporting panel 20 acts as a shifting fulcrum and slides along the back of the easel panel from its vertical locking position to its folded inclined and collapsed position in a path and direction opposite to that shown by the arrow in Fig. 2. In this movement the panel 20 and the band 18 are both necessarily somewhat flexed by pressure on the tip and in some cases it is desirable to flex the tip manually to assist in the collapsing movement. On the other hand, in swinging the section 17 outwardly, the tip is flexed until it arrives at its vertical position with the result that it finally snaps into locked relation to the easel panel and remains unflexed in that position.

Having thus disclosed my invention and described in detail an illustrative embodiment thereof, I claim as new and desire to secure by Letters Patent:

1. A display rack comprising an easel panel of stiff sheet material of substantially rectangular contour with a cut-out in its lower edge into which projects a stop ear, a rectangular section hinged along its straight top edge to the panel, a supporting panel of substantially triangular contour and having a notch in its lower edge providing an edge for contacting said stop ear, and a flexible member connecting the inner side of the hinged rectangular section with the inner side of the supporting panel and passing through the cut-out of the easel panel, said supporting panel having a combined twisting and sliding movement between erected and collapsed condition of the rack.

2. A cardboard display rack comprising an upright easel panel having a flexible triangular support in contact with its rear face, a rectangular section hinged along

5 its entire top edge to the easel panel, and a flexible connecting band merging at one end into the inner edge of the support and at the other into one side of the hinged section, the easel panel having a cut-out therein for the passage of said band, the cut-out being shaped to cause the tip of the support to act as a shifting fulcrum reacting to flex the support in its movement to a right angular operative position.
